COMPRESSING APPARATUS

Alex A. McCormack, Dayton, Ohio, assignor, by
mesne assignments, to General Motors Corpora-
tion, a corporation of Delaware

Application December 23, 1932, Serial No. 648,705
Renewed March 20, 1936

21 Claims. (CL 230—24)

This invention relates to refrigeration and more particularly to a refrigerating system including an improved motor-compressor unit for compressing refrigerant in a refrigerating system.

5 An object of this invention is to provide a motor-compressor unit having an improved form of check valve at the intake which is positively closed when the compressor stops operating, and prevents back flow of refrigerant to the evaporator.

10 Another object of this invention is to provide an improved form of unloader for the motor compressor unit for reducing the starting torque of the unit during the starting period of the motor.

15 Another object of this invention is to provide a motor-compressor unit in which an oscillating type of compressor is enclosed under a cover plate in such a manner as to insure thorough lubrication of the moving parts of the unit.

20 Another object of this invention is to provide an improved construction in which the motor and compressor are resiliently mounted within a sealed casing and in which one of the refrigerant pipes leading to the compressor is secured to the casing and to the resilient frame carrying the motor and compressor in a manner to reduce vibration in the unit.

25 Further objects and advantages of the present invention will be apparent from the following description, reference being had to the accompanying drawings, wherein a preferred form of the present invention is clearly shown.

In the drawings:

30 Fig. 1 is a diagrammatic representation of an apparatus embodying features of this invention;

35 Fig. 2 is a vertical cross-sectional view of a motor-compressor unit embodying features of this invention, the cross section being taken along the line 2—2 of Fig. 3;

40 Fig. 3 is a horizontal cross sectional view of the motor-compressor unit taken along the line 3—3 of Fig. 2;

45 Fig. 4 is another horizontal cross sectional view looking upwardly along the line 4—4 of Fig. 2;

50 Fig. 5 is a vertical cross sectional view of my improved check valve, said view being taken along the line 5—5 of Fig. 4;

Fig. 6 is a horizontal cross sectional view of a portion of the compressor showing a detail of the divider block;

Fig. 7 is a vertical cross sectional view of one form of resilient mounting for the motor-compressor frame;

55 Fig. 8 is a vertical cross sectional view of a

modified form of resilient mounting taken along the line 8—8 of Fig. 9; and

Fig. 9 is a horizontal cross sectional view of the mounting shown in Fig. 8.

A refrigerating apparatus embodying features 5 of this invention includes, in general, a motor-compressor unit having a two-piece, hermetically sealed casing 10 shown in Fig. 1 diagrammatically by a dotted line and being in actual form cylindrical in shape as shown in the other figures. 10 The motor-compressor unit includes a motor generally indicated at 11, having stator windings 12, 13, and 14 and a rotor 15. The rotor 15 is connected by a shaft 17 to a compressor 18. The compressor 18 compresses refrigerant and dis- 15 charges the same through the pipe 19 to the condenser 20 where refrigerant is condensed and from which it is discharged into the receiver 21. From thence the liquid refrigerant flows through the pipe 22 to the evaporator 23, which may be of 20 the well-known float controlled inlet valve type. The refrigerant evaporated at 23 flows through the pipe 24 to the intake of the compressor.

The motor-compressor unit may operate intermittently in accordance with temperatures 25 prevailing in the apparatus and, for example, it may be controlled by a snap switch 25 operated by a bellows 26 which is responsive to the refrigerant pressure in the pipe 24. The snap switch 25 opens and closes the electric circuit 30 which in turn energizes the motor of the unit.

An improved starting control may be provided for the motor of the unit. To this end, the stator winding 12 may be of the well-known starting winding type, the stator winding 14 may 35 be of the well-known running winding type, these two windings being common in the usual split phase motor and forming the energizing stator of the motor. The winding 13 may be an auxiliary or generator winding, the windings 12, 13, 40 and 14 being arranged in a manner similar to windings 4, 5, and 3 described in the patent to Jennings 1,315,965, September 16, 1919. When the motor starts, the winding 12 is energized until the motor attains sufficient speed to operate under the running winding 14, and I have provided an improved control for energizing and deenergizing the starting winding 12 to insure a proper start of the motor. To this end, the lead 27 of the electric circuit is connected to the contacts 28 of the starting relay 29. The contacts 28 are connected to the lead 38 which passes through lead-in plug 38a and is connected to the starting winding 12. The winding 12 is connected to the common lead 31 which passes through 55

lead-in plug 31a. The running winding circuit includes the branch lead 33, solenoid 80, branch 33a, running winding 14 and common lead 31. The solenoid 34 of the starting relay 29 is connected to generator winding 13 which is energized by the rotation of rotor 15. Any suitable circuit may be used to permit a current flow between winding 13 and the solenoid 34; but in order to reduce the number of lead-in plugs in 10 casing 10, the winding 13 may be connected by line with branch 33 before it passes through the lead-in plug 36. From the branch 33, the current flows through lead 27, solenoid 34, line 37, plug 38 to the winding 13.

15 The starting winding control operates as follows: When the switch 25 is closed current flows through the starting winding, the circuit including lead 27, contact 28, lead 30, winding 12 and lead 31. Simultaneously current flows through 20 the running winding 14, the circuit including the branch 33, solenoid 80, branch 33a, winding 14, and branch 31. The flow of current through the windings 12 and 14 starts the motor and when sufficient speed has been attained to permit the 25 motor to operate on winding 14 alone, the current generated in winding 13 reaches a value sufficient to energize the solenoid 34 and open the contacts 28.

The motor and the compressor may be 30 silently mounted within the casing 10, and, to this end, they are supported on a frame 40 which in turn is resiliently mounted in the casing 10 by means of springs 41 placed in the upwardly directed holes 42 in the frame 40. These springs 35 41 rest on individual shelves 43 mounted on the casing 10 which are provided with buttons 44 which position the springs on the shelves 43. The shelves 43 may be provided with resilient stops 45 to limit the permissible vibration of the 40 motor and compressor.

The compressor is provided with a cover plate 46 within the casing 10 which insures proper lubrication of the compressor and permits the lubricant and compressed refrigerant to be 45 forced through the hollow shaft 17 to the lower portion of the casing. The cover plate 46 is secured to the frame 40 by means of bolts 47. The compressor includes an oscillating plate 48 provided with a downwardly directed cylindrical 50 extension 49. The plate 48 rests on the table 50 of the frame 40 and the cylindrical extension 49 operates within the cylinder 51 formed in the frame 40. The plate 48 and cylinder 49 are given an oscillating movement by the eccentric 52 having 55 a ball bearing drive 53 with the plate 48. The plate 48 is prevented from rotating but is permitted to oscillate by a divider block 54 which oscillates about a pin 55 and has a cylindrical 60 cooperating surface 56 concentric with the axis of the pin 55, the surface 56 cooperating with a similar cylindrical surface on the frame 40. In this manner a compressing chamber is formed between the cylindrical extension 49 and the cylinder 51, and the refrigerant is delivered to 65 this chamber through the intake 57 and is discharged upwardly through the plate 48 past the flapper valve 58. Lubricant which gathers in the lower portion of casing 10 is delivered through the filter 61 and the pipe 62 to the passage 63 70 having branches 64 to the surfaces between the cylindrical extension 49 and the block 54 and between the block 54 and the pin 55. Since the refrigerant pressures prevailing at this point are lower than the pressure prevailing within the casing 10, the lubricant flows upwardly and lubricates 75

these surfaces. The lubricant which finds its way to these surfaces in time is discharged through the flapper valve 58 along with the refrigerant and a certain portion of the lubricant remains to lubricate the various moving surfaces 5 of the compressor while the refrigerant and a portion of the lubricant passes through the central opening 70 in the shaft 17 to the lower radial discharge openings 71 at the lower portion of the shaft 17. The central opening 70 is plugged 10 at 72 to prevent discharge of lubricant through the end of the shaft.

An improved unloader for reducing the starting torque is provided. This includes a check valve 14 for the intake of the compressor which 15 check valve includes a valve plate 75 having a stem 76, the plate resting on a valve seat 77. The gas returning from the evaporator 23 passes through the pipe 24 past the annulus 78 and through the pipe 79 to the intake of the compressor. When the compressor stops, by reason of the opening of the snap switch 25, electric current stops flowing through and deenergizes the solenoid 80 which is in series with the running winding 14. The deenergization of the coil 80 20 opens a valve 80a in the line 81 which permits compressed refrigerant to flow through the line 81 to the seat 77 and forces the valve plate 75 firmly against the annulus 78 thus sealing the refrigerant in the motor-compressor unit from the 30 refrigerant in the evaporator 23 thus preventing back flow of refrigerant to the evaporator. This action also equalizes the refrigerant pressures on the intake and discharge of the compressor, and the volumetric capacity of pipe 79 is such that 35 the compressor attains its normal running speed before an appreciable pressure differential can be developed. Thus the compressor is unloaded during the starting period. The solenoid control 80 heretofore described is more fully shown and 40 described in the copending application of George C. Pearce, Serial No. 640,316, filed Oct. 29, 1932, to which reference is hereby made, if necessary, for further disclosure thereof.

One of the pipes leading to the compressor may 45 be connected to the casing 10 and to the compressor and may be coiled in the casing to prevent undue crystallization of the pipe. In this particular embodiment, the intake pipe 79 is spirally coiled about the lower portion of the casing 50 10 and is then secured by the bridge 85 so that the pipe is firmly secured to the resiliently mounted portion of the mechanism coaxially with the shaft 17. This reduces the strains at the connection of the pipe 79 with the frame 40 at the 55 point 86 where the passage 57 leads to the compressing chamber heretofore described.

A modified form of resilient mounting is shown in Figs. 8 and 9 in which a U-shaped spring 90 is secured by the bolt 91 to the block 92 which in 60 turn is secured to the casing 10. The other end of the spring 90 is secured to the block 93 which in turn is secured to the frame 40.

While the form of embodiment of the invention as herein disclosed, constitutes a preferred 65 form, it is to be understood that other forms might be adopted, all coming within the scope of the claims which follow.

What is claimed is as follows:

1. Compressing apparatus comprising a compressor having a gas intake and a gas discharge, means for driving said compressor, an unloader for said compressor including a downwardly directed valve seat on said gas intake, a check valve having an upwardly directed surface engaging 70

5 said valve seat for preventing backward flow of gas through said gas intake, a gas conduit connected to the high pressure side of said compressor and having discharge means for upwardly actuating said check valve, and means for closing said conduit during the running periods of said compressor and for opening said conduit during the idle periods of said compressor.

2. Compressing apparatus comprising a sealed 10 casing, a compressor supported in said casing, a motor in said casing for driving said compressor, a hollow drive shaft connecting said motor and compressor and extending through said compressor, a cover plate over one end of said compressor 15 into which said compressor discharges, said drive shaft having an opening into the space enclosed by said cover plate and discharging the compressed fluid on the other side of said compressor into said casing.

20 3. Compressing apparatus comprising a sealed casing, a compressor supported in said casing, a motor in said casing for driving said compressor, a hollow drive shaft connecting said motor and compressor and extending through said motor, a 25 cover plate over one end of said compressor into which said compressor discharges, said drive shaft having an opening into the space enclosed by said cover plate and discharging the compressed fluid through said motor into said casing.

30 4. Compressing apparatus comprising a sealed casing, a compressor and motor having a drive shaft drivingly connecting said compressor motor within said casing, a frame on which said motor and compressor are mounted, resilient supports 35 in said casing for said frame, a fluid conduit passing through said casing and sealed to said compressor, said conduit having a spiral formation in said casing and being secured to said frame substantially in alignment with said drive shaft.

40 5. Compressing apparatus comprising a casing, a compressor within said casing discharging compressed fluid into the high pressure portion of said casing, a suction connection between the intake of said compressor and the exterior of said casing, 45 a check valve in said suction connection, a passageway from said high pressure portion discharging against said check valve, a valve in said passageway, an electric motor driving said compressor, a solenoid structure closing said last named valve 50 when said electric motor is energized and for opening said last named valve when said motor is deenergized.

6. Compressing apparatus comprising a casing, a compressor within said casing discharging compressed fluid into the pressure portion of said casing, a suction connection between the intake of said compressor and the exterior of said casing, a check valve in said suction connection, a passageway from said high pressure portion discharging 55 against said check valve, a valve in said passageway, an electric motor in said casing driving said compressor, a solenoid structure closing said last named valve when said electric motor is energized and for opening said last named valve when 60 said motor is deenergized.

7. Compressing apparatus comprising a compressor having a gas intake and a gas discharge, means for driving said compressor, an unloader 70 for said compressor including a three-way valve having conduits in communication with the gas intake and the gas discharge of the compressor, and with a source of gas to be fed to said intake, and means responsive to the gas pressure in one 75 of said conduits for operating said valve to con-

nect said gas intake either with the gas discharge or with said source of gas.

8. Compressing apparatus comprising a compressor having a gas intake and a gas discharge, 5 means for driving said compressor, an unloader for said compressor including a three-way valve having conduits in communication with the gas intake and the gas discharge of the compressor and with a source of gas to be fed to said intake, and means responsive to the gas pressure in the 10 conduit communicating with the gas discharge for operating said valve to connect said gas intake either with the gas discharge or with said source of gas.

9. Compressing apparatus comprising a compressor having a gas intake and a gas discharge, 15 means for driving said compressor, an unloader for said compressor including a three-way valve having conduits in communication with the gas intake and the gas discharge of the compressor 20 and with a source of gas to be fed to said intake, and means responsive to the gas pressure in one of said conduits for operating said valve to connect said gas intake either with the gas discharge or with said source of gas, and means for con- 25 trolling the pressure in said one conduit.

10. Compressing apparatus comprising a compressor having a gas intake and a gas discharge, 30 means for driving said compressor, an unloader for said compressor including a three-way valve having conduits in communication with the gas intake and with the gas discharge of the compressor and with a source of gas to be fed to said intake, 35 and means responsive to the gas pressure in one of said conduits for operating said valve to connect said gas intake either with the gas discharge or with said source of gas, and means for controlling the pressure in said one conduit.

11. Compressing apparatus comprising a com- 40 pressor having a gas intake and a gas discharge, 45 means for driving said compressor, an unloader for said compressor including a three-way valve having conduits in communication with the gas intake and the gas discharge of the compressor and with a source of gas to be fed to said intake, 50 and means responsive to the gas pressure in the conduit communicating with the gas discharge for operating said valve to connect said gas intake either with the gas discharge or with said source of gas, and means for controlling the pressure in the conduit communicating with the gas discharge.

12. Compressing apparatus comprising a compressor having a gas intake and a gas discharge, 55 means for driving said compressor, an unloader for said compressor including a three-way valve having conduits in communication with the gas intake and the gas discharge of the compressor and with a source of gas to be fed to said intake, 60 and means responsive to the gas pressure in the conduit communicating with the gas discharge for operating said valve to connect said gas intake either with the gas discharge or with said source of gas, and valve means for controlling the pressure in the conduit communicating with the gas discharge.

13. Compressing apparatus comprising a sealed 70 casing, a motor in said casing, a compressor in said casing driven by said motor and having a discharge adjacent one end of said casing, means forming a closed conduit for conducting compressed gas to the opposite end of said casing, and an outlet from said casing adjacent said one end thereof.

14. Compressing apparatus comprising a sealed casing, a motor in said casing, a compressor in said casing driven by said motor and having a discharge adjacent the top of said casing, means forming a closed conduit for conducting compressed gas to the lower end of said casing, and an outlet from said casing adjacent the top thereof.
15. Compressing apparatus comprising an electric motor, a compressor driven thereby and having a gas intake and a gas discharge, means for driving said compressor, an unloader for said compressor including a three-way valve having conduits in communication with the gas intake and the gas discharge of the compressor and with a source of gas to be fed to said intake, and means responsive to starting electrical conditions in said motor and the gas pressure in one of said conduits for operating said valve to connect said gas intake either with the gas discharge or with said source of gas.
16. Compressing apparatus comprising an electric motor, a compressor driven thereby and having a gas intake and a gas discharge, means for driving said compressor, an unloader for said compressor including a three-way valve having conduits in communication with the gas intake and the gas discharge of the compressor and with a source of gas to be fed to said intake, and means responsive to starting electrical conditions in said motor and the gas pressure in the conduit communicating with the gas discharge for operating said valve to connect said gas intake either with the gas discharge or with said source of gas.
17. Compressing apparatus comprising an electric motor, a compressor driven thereby and having a gas intake and a gas discharge, means for driving said compressor, an unloader for said compressor including a three-way valve having conduits in communication with the gas intake and the gas discharge of the compressor and with a source of gas to be fed to said intake, and means responsive to starting electrical conditions in said motor and the gas pressure in one of said conduits for operating said valve to connect said gas intake either with the gas discharge or with said source of gas, and means for controlling the pressure in said one conduit.
18. Compressing apparatus comprising an electric motor, a compressor driven thereby and having a gas intake and a gas discharge, means for driving said compressor, an unloader for said compressor including a three-way valve having conduits in communication with the gas intake and the gas discharge of the compressor and with a source of gas to be fed to said intake, and means responsive to starting electrical conditions in said motor and the gas pressure in one of said conduits for operating said valve to connect said gas intake either with the gas discharge or with said source of gas, and means for controlling the pressure in said one conduit.
19. Compressing apparatus comprising an electric motor, a compressor driven thereby and having a gas intake and a gas discharge, means for driving said compressor, an unloader for said compressor including a three-way valve having conduits in communication with the gas intake and the gas discharge of the compressor and with a source of gas to be fed to said intake, and means responsive to starting electrical conditions in said motor and the gas pressure in the conduit communicating with the gas discharge for operating said valve to connect said gas intake either with the gas discharge or with said source of gas, and means for controlling the pressure in the conduit communicating with the gas discharge.
20. Compressing apparatus comprising an electric motor, a compressor driven thereby and having a gas intake and a gas discharge, means for driving said compressor, an unloader for said compressor including a three-way valve having conduits in communication with the gas intake and the gas discharge of the compressor and with a source of gas to be fed to said intake, and means responsive to starting electrical conditions in said motor and the gas pressure in the conduit communicating with the gas discharge for operating said valve to connect said gas intake either with the gas discharge or with said source of gas, and means for controlling the pressure in the conduit communicating with the gas discharge.
21. Compressing apparatus comprising a sealed casing, a motor in said casing, a compressor in said casing driven by said motor and having a discharge adjacent one end of said casing, means forming a closed conduit for conducting compressed gas to the opposite end of said casing, and an outlet from said casing adjacent said first named end thereof.
